UNITED STATES PATENT OFFICE.

SAMUEL SEGAL, OF NEW YORK, N. Y., ASSIGNOR TO SEGAL LOCK & HARDWARE CO., INC., OF NEW YORK, N. Y., A CORPORATION OF NEW YORK.

CYLINDER LOCK.

Application filed January 6, 1926. Serial No. 79,535.

This invention relates to an improved cylinder type lock.

It is an object of the invention to furnish a cylinder lock in which several manufacturing steps heretofore resorted to may be dispensed with.

A further object is that of constructing a lock particularly of the type specified in which the parts will be maintained in proper 10 operative relationship over the entire life of the lock so as to prevent a jamming of the parts, and, in some instances, a breakage of the key.

An additional object is that of providing 15 a lock which will efficiently perform the purposes for which it is intended, and which will also be economically and readily manufactured and easily assembled and disassembled.

Other objects of the invention will in part 20 be obvious and will in part appear hereinafter.

The invention accordingly comprises the features of construction, combination of elements and arrangement of parts which will be exemplified in the construction hereinafter set forth, and the scope of the application of which will be indicated in the claims.

For a fuller understanding of the nature 30 and objects of the invention reference should be had to the following detailed description taken in connection with the accompanying drawings, in which:

Figure 1 is an end view of a cylinder lock 35 embodying one form of the invention;

Fig. 2 is a partly fragmentary sectional side elevation thereof;

Fig. 3 is a transverse view of the device 40 as shown in Fig. 2 taken along the lines 3—3 and in the direction of the arrows of Fig. 1;

Figs. 4, 5 and 6 are views corresponding to 45 Figs. 1, 2 and 3 respectively, but showing a different form of the invention from that shown in the preceding figures;

Fig. 7 is a fragmentary enlarged sectional view of a detail of construction which may be employed;

Fig. 8 is a sectional view of certain of the parts as shown in Figs. 1, 2 and 3;

Fig. 9 is a side elevation of a lock tailpiece such as is preferably employed in connection with a cylinder lock of this type; and

Fig. 10 is a view similar to Fig. 7.

In Figs. 1 to 6 the numeral 10 indicates the 55 lock cylinder, within the bore of which a plug

11 is positioned, the latter being formed with a key slot 12 and having an enlarged end-portion 13 to prevent its movement rearwardly within the cylinder. It will be understood that in the present exemplification the 60 pins, springs and tumblers associated with the key plug and the cylinder have not been shown, and they may be of any desirable character.

Contrary to conventional construction, according to which the plug terminates at a point immediately adjacent or beyond the rear face of the cylinder, it will be seen that according to the present invention the plug 65 may be materially extended beyond the cylinder bore, as has been indicated at 14. Also, if desired, and as has been shown in Figs. 4 to 7 inclusive, this rear end of the plug may be reduced as at 15, but this is largely a matter of manufacturing convenience, and in 70 any event, the key slot 12 may extend through to this plug end.

As has been shown in Figs. 1, 2 and 3, the cylinder casing 10 may be formed with a pair of recesses or pockets 16, against the bases of 75 which the ends of springs 17 bear, these springs extending beyond the rear cylinder face. The portion 14 of the plug is formed with a transverse bore 18 intersecting the key slot 12, and at this point the plug is encircled by a washer or collar 19, which, in the present instance, has downwardly-extending lugs 20 at diametrically opposite points, and which are of a size sufficiently small to extend within the bodies of the springs. A tail-piece or connecting bar 21 is formed at one 80 of its ends with an opening 22, and this end is positioned within the key slot or other recess formed in the extended plug portion 14, and the opening 22 is aligned with the bore 18. 85

It will here be observed that according to conventional construction the inner end of the tailpiece, i. e., that end of the same which was directly coupled to the plug, was usually enlarged so as to prevent its detachment from 90 the end disk which was secured to the plug by means of screws. According to the present invention, however, it is unnecessary to enlarge this tailpiece in that with the opening 22 in line with the bore 18 a pin 23 may 100 be slipped through this bore and thus secure the parts against material relative movement. The ends of the pin 23 may be enlarged as at 24 and will be acted upon by the washer or collar 19 which is pressed outwardly by the 105 110

spring 17. Thus the axis of the pin will be displaced with respect to the axis of the bore, and the undercut portions of the pin adjacent the inner edges of the pinheads or enlarged portions will engage the side face of the plug and prevent any accidental displacement of the pin. At this time it will be understood that due to the fact that the pin is located within the extended portion of the plug it will in no wise interfere with the operation of the lock by means of the key, for the reason that if, as in the present embodiments, the pin does bridge the key slot itself it is located beyond the point to which the key ends extends. By means of this construction it will be obvious that a constant pressure will be exerted upon the plug in a rearward direction, and any wear of the parts will be automatically taken up, and there will be no danger of these parts loosening.

With final specific reference to this form, the washer or collar 19, as in Fig. 8, may be formed with grooves 25 in its outer face and at points in line with the lugs or arms 20. Thus, an operator will know when the pins and tumblers (not shown) of the lock are in line due to the fact that there will be a faint click when the parts reach this position. Furthermore, as the lock is operated the washer will compress the springs, so that the life of the springs will be maintained. By this construction it will also be obvious that with a key not in position the relative positions of the cylinder and plug will be maintained.

In the form of the invention shown in Figs. 4, 5 and 6 the parts are preferably similar in all respects to those shown in the preceding views, with the exception that the end or extended portion of the plug is encircled by a spring 26, which is interposed between and has its ends bearing against washers 27 and 28, the outer face of the latter in turn engaging the headed ends of the pin. In this form of device it is of course unnecessary to provide a multiplicity of springs or to form the cylinder casing with pockets or recesses such as 16 in the preceding views, and it will be equally obvious that in this exemplification, as in the preceding form, a constant pressure will be exerted to retain the plug in proper position with respect to the parts with which it is associated.

If it is not desired to utilize a headed pin it will be noted that as in Fig. 7 a plain pin 29 may be employed, and the washer 30 may have its outer edge flanged upwardly as at 31 (by extrusion or in any other desirable manner) and at points beyond the pin ends so as to present a pin-confining structure to accomplish the results desired.

In both of the embodiments illustrated it will be appreciated that due to the fact that the plug always remains in properly seated relationship with respect to the cylinder parts

there will be no danger of play coming into existence such as would disalign the plug and cylinder pins and cause a jamming of the lock. Furthermore, by means of such a construction as is proposed it is unnecessary to carefully grind the end of the plug and apply an end disk thereto in order to prevent its displacement. Furthermore, it is unnecessary to tap and thread the end of the plug, and it will be obvious that the work of assembling can be accomplished with facility.

Finally, with reference to Fig. 10 it will be noted that, if desired, a washer of the nature illustrated in this figure may be employed in lieu of that shown in Figs. 1, 2 and 3. This washer includes a body 32 encircling the end of the plug and having portions struck out as at 33, which portions serve the same purpose as the lugs 20. By a construction of this nature the edges of the washer overlap and protect the ends of the springs. Also, if desired, in lieu of the pins shown in these several views a pin may be employed which has a thickened body 34 and reduced end-ports 35. It will be obvious that this pin may be threaded through the bore to secure the tailpiece as aforescribed, and that the washer, under the influence of the spring or springs, will bear against the reduced end-ports and override the shoulders adjacent thereto, as a consequence retaining the pin against movement.

Furthermore, it will be noted in this view that the pin may be formed with an annular groove 36, against the sides of which the edge of the tailpiece may bear in order to further preclude against the possibility of displacement of the pin.

Thus, among others, the objects of this invention have been accomplished, and since certain changes may be made in the above construction, and different embodiments of the invention could be made, without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. A lock, including, in combination, a cylinder, a rotatable plug extending into the bore of said cylinder, a head portion at one end of said plug and bearing against a seat formed in said cylinder, and means for yieldingly urging the head of said plug against said seat.

2. A lock, including, in combination, a

- 5 cylinder, a rotatable plug extending into the bore of said cylinder, a head portion at one end of said plug and bearing against a seat formed in said cylinder, and means at the opposite end of said plug for constantly forcing the head of the same into contact with said seat.
3. A lock, including, in combination, a cylinder, a rotatable plug extending into the bore of said cylinder, a head portion at one end of said plug and bearing against a seat formed in said cylinder, the end of said plug extending materially beyond said cylinder, and means associated with said extending end-positions and said cylinder for constantly urging the head of said plug into seated relationship with respect to said cylinder.
4. A lock, including, in combination, a cylinder, a plug rotatably positioned within the bore of said cylinder, resilient means for constantly urging said plug inwardly with respect to said cylinder, and a tailpiece connected to the end of said plug.
5. A lock, including, in combination, an uninterrupted cylinder housing, a plug rotatably positioned within the bore of said cylinder and to be rotated by being acted upon by a proper key, and resilient means for constantly urging said plug inwardly with respect to said cylinder.
6. A lock, including, in combination, a cylinder, a plug rotatably positioned within the bore of said cylinder, a tailpiece comprising a strip of material having a substantially straight end-portion, and means for associating the end-portion of said tailpiece with said plug.
7. A lock, including, in combination, a cylinder, a plug rotatably positioned within said cylinder and extending materially beyond the end of the same, a washer encircling the end-portion of said plug, means connecting said washer with said plug, and resilient means acting upon said washer and tending to retain said plug in applied position.
8. A lock, including, in combination, a cylinder, a plug rotatably positioned within said cylinder and extending materially beyond the end of the same, a washer encircling such end of the plug, a pin associated with the latter and contacting with the former, and resilient means acting against said washer for constantly urging the parts into proper position.
9. A lock, including, in combination, a cylinder, a plug rotatably positioned within said cylinder and extending materially beyond the end of the same, said plug being formed with a transverse bore, a pin positioned within said bore, a washer encircling said plug and contacting with the ends of said pin, and a spring engaging said washer and urging the same outwardly with respect to said cylinder.
10. A lock, including, in combination, a cylinder, a plug rotatably positioned within said cylinder and extending materially beyond the end of the same, said plug being formed with a transverse bore, a pin positioned within said bore and having enlarged heads, a washer encircling said plug and contacting with the ends of said pin, and a spring engaging said washer and urging the same outwardly with respect to said cylinder.
11. A lock, including, in combination, a cylinder, a plug rotatably positioned within said cylinder and extending materially beyond the end of the same, said plug being formed with a transverse bore, a pin positioned within said bore, a washer encircling said plug and contacting with the ends of said pin, and a spring engaging said washer and urging the same outwardly with respect to said cylinder, the edges of said washer being flanged upwardly at points beyond the ends of said pin whereby said washer acts as a confining member for said pin.
12. A lock, including, in combination, a cylinder, a plug rotatably positioned within said cylinder and extending materially beyond the end of the same, a washer encircling said plug end and being operatively connected therewith, inwardly-extending lugs forming a part of said washer, and springs encircling said lugs and seating within recesses formed in said cylinder.
13. A lock, including, in combination, a cylinder, a plug rotatably positioned within said cylinder and extending materially beyond the end of the same, a washer encircling such end of the plug and having depressions formed in its upper face, means for urging said washer outwardly, and a pin associated with the plug end and riding into the depressions formed in said washer face.
14. A lock, including, in combination, a cylinder, a plug rotatably positioned within said cylinder and extending materially beyond the end of the same, a spring encircling the end-portion of said plug, and a pin associated with said plug end, said spring acting against said pin.
15. A lock, including, in combination, a cylinder, a plug rotatably positioned within said cylinder and extending materially beyond the end of the same, a washer encircling said plug end and being operatively connected therewith, lugs struck inwardly from said washer, and springs encircling said lugs and seating within recesses formed in said cylinder, said washer extending beyond said springs.
16. A lock, including, in combination, a cylinder, a plug rotatably positioned within said cylinder and extending materially beyond the end of the same, said plug being formed with a transverse bore, a pin positioned within said bore and having reduced end-positions extending beyond the same, a washer encircling said plug and contacting

with the ends of said pin, and a spring co-operating with said washer and urging the same outwardly with respect to said cylinder.

17. A lock, including, in combination, a cylinder, a plug rotatably positioned within said cylinder and having its rear end extending materially beyond the same, and means associated with the extended portion of the plug and acting constantly against the rear face of the cylinder to maintain said plug against axial shifting with respect to the cylinder incident to wearing of the parts.

18. A lock, including, in combination, a cylinder, a plug rotatably carried by said cylinder and being formed with a transverse slot in its rear end, a tail-piece extending into said slot and being formed with an opening, a pin carried by the rear end of the tail-piece and extending across said slot and through the opening to retain said tail-piece in position with respect to the plug and means for maintaining said pin against displacement.

19. A lock, including, in combination, a cylinder, a plug rotatably carried by said cylinder, and means extraneous of the lock pins and tumblers for maintaining said plug against rotation and in a predetermined fixed position with respect to said cylinder.

20. A lock, including, in combination, a cylinder, a plug rotatably carried by said cylinder and extending beyond the rear face thereof, a tail-piece, and normally locked, readily releasable means associated with the extended portion of said plug and engaging said tailpiece whereby the latter may be readily detached from or secured to said plug.

21. In combination a cylinder formed with a bore, a plug rotatable within said bore and means extraneous of the locking mechanism

associated with said cylinder and plug and tending to maintain the latter against any rotation with respect to the former.

22. A lock cylinder assembly including a cylinder, a plug rotatably carried within the latter, locking elements associated with said plug and cylinder and to be key-actuated and released and further means tending automatically to maintain said plug against rotation and set the same in predetermined position with respect to the cylinder.

23. A lock including a cylinder formed with a bore, a plug rotatable within said bore, said plug being formed with an opening adjacent its rear end, a pin disposed within said opening and extending beyond the same and a spring acting against said pin to maintain the plug automatically against axial shifting.

24. A lock including, in combination, a cylinder formed with a bore, a plug rotatable within said bore and being formed with a key-slot into which a key is to be introduced to rotate the plug with respect to the cylinder and means for automatically maintaining said plug and the slot therein in such position with respect to the cylinder that the introduction of said key may be effected into said slot.

25. A lock including a cylinder formed with a bore, a plug rotatable within said bore and being formed with a transverse opening adjacent its rear end, a headed pin disposed within said opening and a spring acting against said pin to urge said plug into predetermined position with respect to the cylinder and to maintain, automatically, said pin against displacement from said opening.

In testimony whereof I affix my signature.

SAMUEL SEGAL.
